UNITED STATES PATENT OFFICE.

GEORGE R. COTTRELL, OF NEW YORK, N. Y., ASSIGNOR OF ONE-HALF TO
W. W. DUDLEY AND FRANK C. BROWNE, OF WASHINGTON, DISTRICT OF
COLUMBIA.

APPARATUS FOR MIXING GAS AND AIR.

SPECIFICATION forming part of Letters Patent No. 556,490, dated March 17, 1896.

Application filed March 18, 1892. Serial No. 425,471. (No model.)

To all whom it may concern:

Be it known that I, GEORGE R. COTTRELL, a citizen of the United States, residing at New York, in the county of New York and State of New York, have invented certain new and useful Improvements in Apparatus for Mixing Gas and Air; and I do declare the following to be a full, clear, and exact description of the invention, such as will enable others skilled in the art to which it appertains to make and use the same, reference being had to the accompanying drawings, and to the letters and numerals of reference marked thereon, which form a part of this specification.

My present invention has reference to improvements in apparatus for mixing gas and air, and has for its object to produce a machine embodying simplicity of construction and operation, and in which the pressure of the gas alone is utilized as the motive power.

My invention consists generally in a cylinder or casing inclosing two screw-drums, one for the gas and one for the air, which are simultaneously rotated by the action of the pressure of the gas, the mixture of the gas and air being accomplished within the cylinder.

In the following description is set forth an apparatus embodying all the features of my present invention, and in which the construction, relative arrangement, and operation of the several parts constituting such apparatus will become apparent.

In the accompanying drawings, which form a part of this specification, Figure 1 represents an elevation of the apparatus; Fig. 2, a central longitudinal vertical section of the same; Fig. 3, a vertical cross-section of the same; Fig. 4, the receiving end of the screw-drum for the gas; Fig. 5, the discharging end of the same, and showing in dotted lines the positions of the openings in the discharging end of the screw-drum for the air in relation thereto; and Fig. 6 is a detail of a section of the gas-supply pipe with a pressure-regulator connected thereto.

Referring to the drawings, in which like letters and numerals of reference refer to like parts in all the figures, the letter A denotes the cylinder or casing which contains the operat-

ing mechanism, and which is mounted on standards or legs *a* or may be secured to a wall or other upright by brackets or other preferred means. Within this cylinder are arranged two screw-drums, one of which, B, is for the gas, and should preferably have a length equal to about one-fourth of the length of the screw-drum C for the air. These drums are mounted on a shaft *d* and are preferably arranged eccentrically to the center of the cylinder in order to provide the greater space at the top and furnish a chamber of comparatively large area for the reception of the gas and air. The lower portion of the drums would in this event just clear the bottom of the cylinder, and as this portion is submerged it is evident that there could be no utility in providing a space at this point. By this arrangement also the amount of water to be displaced is materially lessened. The shaft *d* is preferably square in cross-section and is journaled in cone-bearings arranged in the gas and air supply pipes at opposite ends of the cylinder, as shown. At the receiving end of each drum is arranged a casing *e* which is beveled at its periphery, as shown at *e'*, to give greater space within the cylinder and to offer as little resistance in its passage through the water as possible. These casings form chambers *e*² which confine the air or gas, as the case may be, and deliver it to the receiving ends of the drums. The heads of the cylinder and casings are perforated to receive the gas and air supply pipes, which are of the elbow type and extend upward within the chambers *e*² to a point above the water-level.

The drums are of similar construction to the drums shown and described in the patent granted to me March 3, 1891, and numbered 447,299, each of which being provided with a series of spirally-arranged compartments, the receiving ends of which are adjacent to the chambers *e*² and the discharging ends terminating at the inner ends of the drums. In the present instance, however, the spiral compartments in the gas-drum are arranged in lines opposite to the lines of the compartments in the air-drum, and, as shown in Fig. 5, the discharging ends 1 of the former are located at points midway between the dis-

charging ends 2 of the latter. By this arrangement of the relative positions of the discharging ends of the drums 1 attain a positive sealing action in both drums, as it will be evident if the openings were arranged in lines coincident with each other the sealing action in both drums would be the same and at certain points the gas under pressure would have a clear passage through both drums, and this would be the case even when a portion of a compartment contained water, as the full pressure of the gas would tend to displace the water and escape from the apparatus.

The drums are mounted and arranged in such a manner as that little or no friction is produced in the operation, and the pressure of the gas alone is sufficient to cause said drums to revolve and deliver the gas and air to the mixing-chamber. By this arrangement I dispense with the gearing and weight and other mechanisms heretofore employed and produce a steady and constant rotation of the drums.

Water is supplied to the cylinder through a pipe *f* which is normally closed by a screw-cap *g*. This pipe extends within the cylinder and has a branch *h* arranged at a point coincident with the level the water properly assumes, and which is closed by a cap *i*. When water is to be introduced both caps are removed and water is fed until the water reaches the level of the branch through which it flows and indicates that the proper amount has been supplied.

In Fig. 6 I have shown a device for regulating the pressure of the gas from the main, and which consists of a perforated diaphragm *k* which has a central opening to admit a small rod *l*, to which is connected a disk valve *m* and a follower *n*. The follower is also perforated and a pressure above normal operates to raise the follower and valve to partially close the openings in the diaphragm. A spiral spring *l'* operates to keep the valve *m* normally opened, and the spring when fully compressed operates as a stop to prevent the supply of gas being entirely cut off.

I arrange on the casing of the air-drum a trip *o* which operates at each complete revolution of the drum to engage one tooth of a gear *p* which is suitably mounted in the cylinder. This gear operates by means of other suitable gearing a set of dials which register the number of revolutions of the drum and indicate the number of feet of mixed air and gas which is discharged from the apparatus. It is evident, however, that similar mechanism could be employed in connection with the apparatus to measure or indicate the amount of gas or air which is supplied to the machine.

The operation of my improved apparatus is as follows: Water is first introduced into the cylinder until the predetermined level is reached. The gas is then turned on and supplied to the gas screw-drum, which is rotated

by the pressure thereof and imparts motion to the air screw-drum through the shaft *d* on which both drums are mounted. The air and gas entering the spiral compartments of their respective drums is discharged therefrom when the revolution of the drums brings the discharging ends of the compartments above the level of the water, and the gas and air passing to the upper portion of the cylinder are thoroughly mixed and delivered by the outlet *x* to the point or points of consumption. The gas enters the compartments under full pressure from the main, but leaves under a comparatively low pressure created solely by the revolution of the drum in the water, and consequently the mixed gas and air is delivered at a low pressure. By reason of the device employed in connection with the apparatus for registering the quantity of gas or air or gas and air combined which passes through the apparatus the necessity of employing a gas-meter is obviated, as my apparatus serves the double purpose of combining and mixing the gas and air and recording the quantity consumed.

The apparatus when constructed in accordance with my invention is very simple in construction and may be cheaply made, as it is my purpose to form the cylinder in two sections having flanges, which are bolted together when the mechanism is placed within the same, as shown.

The apparatus when made is very compact, is neat and attractive in appearance and in view of the simple construction and few parts is not likely to get out of order.

As before stated the pressure of the gas alone serves as the motive power to rotate the drums, and by the employment of a pressure-regulator in connection with the gas-supply a steady and constant operation and flow of mixed gas and air is the result.

I claim—

1. In an apparatus of the class described the combination with a cylindrical casing having an outlet-pipe for mixed air and gas, an inlet-pipe for air, an inlet-pipe for gas, said inlet-pipes arranged respectively at opposite ends of said casing and provided with journal-bearings, two drums mounted on a single shaft eccentrically in said casing and upon said bearing, each of said drums being divided by means of a partition into two compartments, one of which compartments communicating with the inlet-pipe for air and gas respectively, and the other compartment divided by spiral blades into suitable chambers and communicating with the inlet-compartment and having the discharge end of said spiral compartment provided with discharge-openings, the discharge-openings of one drum being adjacent to but out of line with the discharge-openings of the other drums, substantially as described.

2. In an apparatus of the class described,

the combination with a cylindrical casing containing screw-drums, of a water-supply or filling pipe leading from the inlet in the top of the casing and extending downward concentrically with the interior of the casing to a point near the base, an overflow branch in said pipe, and closures for the latter and the water-inlet.

In testimony whereof I affix my signature in presence of two witnesses.

GEORGE R. COTTRELL.

Witnesses:

ARTHUR BROWNING,
WILL T. NORTON.

It is hereby certified that the name of the last-mentioned assignee in Letters Patent No. 556,490, granted March 17, 1896, upon the application of George R. Cottrell, of New York, N. Y., for an improvement in "Apparatus for Mixing Gas and Air," was erroneously written and printed "Frank C. Browne," whereas said name should have been written and printed "*Frank L. Browne*"; and that the said Letters Patent should be read with this correction therein that the same may conform to the record of the case in the Patent Office.

Signed, countersigned, and sealed this 24th day of March, A. D 1896.

[SEAL.]

JNO. M. REYNOLDS,
Assistant Secretary of the Interior.
